UNITED STATES PATENT OFFICE.

AUGUSTUS L. WHITNEY, OF HARVARD, MASSACHUSETTS.

IMPROVEMENT IN SASH-HOLDERS.

Specification forming part of Letters Patent No. **147,726**, dated February 17, 1874; application filed January 28, 1874.

To all whom it may concern:

Be it known that I, AUGUSTUS L. WHITNEY, of Harvard, in the county of Middlesex and State of Massachusetts, have invented an Improved Sash-Supporter; and I do hereby declare that the following, taken in connection with the drawings which accompany and form part of this specification, is a description of my invention sufficient to enable those skilled in the art to practice it.

The invention relates to the construction of a device for supporting a window-sash by frictional pressure, instead of by counterbalance-weights.

In my invention I use a long metal case set into a slot cut for its reception in the side bar of the sash, and in this case I place a frame, in which is journaled a friction-roll, this frame sliding between guideways formed in the case, and being pressed forward by the stress of a strong spring. When the case is secured in the sash slot or mortise, and the sash is placed in the window-frame, the roll or frame is pressed back and held by the window-frame against the stress of the spring, but the spring-pressure is such that, although the roll turns freely for the sash to be raised or lowered by pressure of the hand, yet it holds the sash firmly in any position when free from such pressure.

My invention consists in the sash-retaining device constructed as thus generally described.

The drawing represents a construction embodying my invention.

Figure 1 shows the same in front view. Fig. 2 is a sectional elevation of it. Fig. 3 is a central cross-section. Fig. 4 shows the roll in position to support the sash. *a* denotes the metal case, to be set in a mortise formed to receive it in the edge of the vertical rail of the sash. This case has a deep socket, and at the central part the case is formed with guide-ribs *b*, between which plays a frame, *c*, that carries the presser-roll *d*, the roller turning on a pin, *e*, extending through the frame. Back of the frame *c* is a spring, *f*, which bears against the frame and tends to project the outer side of the roller beyond the case. This spring may be a leaf-spring, as seen in the drawing, or a spring of any other suitable form or construction. The roll is held back when the sash is in place, but is at all times pressed forward by the spring, and with sufficient stress to maintain the sash in any position to which it may be raised.

I claim—

The sash-supporter having a roll journaled in a frame, *c*, which frame slides between guides *b* in a case, *a*, and is pressed forward by the stress of a spring, all substantially as shown and described.

AUGUSTUS L. WHITNEY.
